UNITED STATES PATENT OFFICE.

JOHN R. ROBINSON, OF WHITTIER, CALIFORNIA.

ENGINE-MUFFLER.

1,109,547.

Specification of Letters Patent.

Patented Sept. 1, 1914.

Application filed December 19, 1912. Serial No. 737,747.

To all whom it may concern:

Be it known that I, JOHN R. ROBINSON, a citizen of the United States, residing at Whittier, in the county of Los Angeles, State of California, have invented certain new and useful Improvements in Engine-Mufflers; and I do hereby declare the following to be a full, clear, and exact description of the invention, such as will enable others skilled in the art to which it appertains to make and use the same.

This invention relates to mufflers and has for an object to provide a muffler from which the gases are sucked out during the exhaust stroke of the engine and in which a vacuum is created in the muffler during the compression stroke so that back pressure will be positively eliminated.

With the above objects in view the invention consists of certain novel details of construction and combination of parts herein-after fully described and claimed, it being understood that various modifications may be made in the minor details of construction within the scope of the appended claim.

In the accompanying drawings forming part of this specification: Figure 1 is a diagrammatic view showing the application of my invention. Fig. 2 is a longitudinal sectional view through the muffler. Fig. 3 is a fragmentary sectional view showing the release valve of the muffler in open position.

Referring now to the drawings in which like characters of reference designate similar parts, 10 designates an internal combustion engine, 11 designates the muffler, and 12 the exhaust fan, the latter being continuously actuated from the crank shaft of the engine by means of a chain drive 13. The exhaust manifold 14 of the engine is connected by a pipe 15 to the muffler, and a pipe 16 connects the muffler with the exhaust fan. The burnt gases are exhausted from the muffler continuously by the exhaust fan so that on the exhaust stroke of the engine the muffler will be quickly purged of burnt gases while on the compression stroke of the engine a partial vacuum will be created in the muffler to hasten the purging of the muffler on the next succeeding exhaust stroke and thus positively obviate back pressure.

In the present embodiment of my invention I employ in the construction of the muffler 10, a cylindrical casing 17 which is closed at each end by disk heads 18 and 19 respectively, and within the casing are ar-

ranged a plurality of concave disk baffles 20, these baffles being each formed with a central opening 21, and the openings of all the baffles being in registration. The exhaust pipe 15 from the engine enters the disk head 19 and registers with the central openings of the baffles. The suction pipe 16 of the fan is provided terminally with a U-shaped terminal 22 which embraces the casing longitudinally, the branches 23 of the pipe being each provided with a series of intake nozzles 24 which project into the casing between and alternate with the baffles. The exhaust from the engine upon entering the casing expands into the various compartments formed by the baffle and is from thence drawn off through the nozzles 24 by the suction of the fan.

Formed in the head 18 of the muffler casing is a port 25 which is normally closed by an outwardly opening valve 26, the stem 27 of which is equipped with a helical spring 28 that bears against the inner wall of the casing and serves to hold the valve closed under ordinary exhaust pressure. Upon an explosion taking place in the muffler the valve will be forced open against the tension of its spring by the abnormal pressure of the explosion and will permit of the abnormal pressure releasing through the port 25.

The fan 12 comprises a cylindrical casing 29 the ends of which are closed by disk heads 30 and 31, and within the casing a shaft 32 is axially disposed and is equipped with fan blades 33. One end of the shaft projects from the casing and is equipped with a sprocket gear 34 which is rotated from the crank shaft by the above described chain drive 13. Ball bearing boxes 35 and 36 are attached to the heads 30 and 31 and journal the shaft. The suction pipe 16 is formed with a U-shaped terminal 37 which is connected to the head 30. An outlet pipe 38 is provided with a branched terminal 39 which is connected to the head 31. The burnt gases drawn into the fan casing by the suction of the fan are discharged from the casing through the outlet pipe 38.

What is claimed is:

A muffler including a cylindrical casing, a plurality of dished baffles forming partitions transverse of said casing, an engine exhaust pipe entering one end of said casing on the longitudinal axis of said casing, all of said baffles having their central por-

tions depressed inwardly and formed with central openings that align with said exhaust pipe, a release valve in the opposite end of said casing in alignment with said exhaust pipe, and a suction pipe of substantially U-shape embracing said casing longitudinally and having a plurality of nozzles on each leg entering said casing, the nozzles of each leg being in alignment with

each other and projecting beyond the inner wall of the casing and into the spaces between said baffles.

In testimony whereof, I affix my signature, in the presence of two witnesses.

JOHN R. ROBINSON.
